Primary Examiner — Ricky Pham

(74) **Attorney, Agent, or Firm:** CANTOR COLBURN LLP

(57) **CLAIM**

The ornamental design for an electric cooking pot, as shown and described.

DESCRIPTION

FIG. 1 is a front perspective view of an electric cooking pot, showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is a bottom perspective view thereof;

FIG. 9 is a cross sectional view taken through line 9-9 of FIG. 2;

FIG. 10 is a cross sectional view taken through line 10-10 of FIG. 6; and,

FIG. 11 is another front perspective view thereof with unclaimed cast-iron cookware.

The even-dash broken lines illustrating portions of the electric cooking pot form no part of the claimed design.

1 Claim, 11 Drawing Sheets
